UNITED STATES PATENT OFFICE.

BRODERICK HASKELL, OF GRAND RAPIDS, MICHIGAN.

CARPET-SWEEPER.

SPECIFICATION forming part of Letters Patent No. 610,603, dated September 13, 1898.

Application filed March 11, 1898. Serial No. 673,443. (No model.)

To all whom it may concern:

Be it known that I, BRODERICK HASKELL, a citizen of the United States, residing at Grand Rapids, in the county of Kent and State of Michigan, have invented certain new and useful Improvements in Carpet-Sweepers; and I do hereby declare the following to be a full, clear, and exact description of the invention, such as will enable others skilled in the art to which it appertains to make and use the same.

My invention relates to improvements in carpet-sweepers; and its object is to provide the same with means for preventing the escape of fine dust from beneath the case and collecting the same; and it consists, essentially, in combining with a carpet-sweeper a blower to create an inward draft of air between the case and carpet and to discharge the same through a passage in which is a dust-collector, as hereinafter more fully described, and particularly pointed out in the claims, reference being had to the accompanying drawings, in which—

Figure 1 is a transverse vertical section of a device embodying my invention, taken on the line 1 1 of Figs. 2 and 3; Fig. 2, a longitudinal vertical section of the same on the line 2 2 of Fig. 1; and Fig. 3, a plan view of the same, with parts broken away to show the construction.

Like letters refer to like parts in all of the figures.

A represents the case, of substantially the usual form, having the rotary brush E and means for rotating the same and provided with an opening A' in one of its inclined sides for egress of air from the blower and a door A" through which to insert and remove the sponge G, which sponge is located in an air-passage B, extending inward from the opening A' to the blower-casing B'. Said passage and casing are preferably formed by a continuous strip of sheet metal extending horizontally from the lower side of the opening A' to about the middle of the case, and thence in a curve around the axis of the shaft carrying the fan, terminating in an incomplete cylinder, leaving an opening for escape of air at the side toward the opening A'. The end walls of this casing and passage are formed

by flat plates, and the top of the passage from the casing of the fan to the opening A' is formed by the top of the case A. These parts are also provided with wire screens F and F' 55 to retain the sponge G in place and axial openings B" in the end walls of the casing B' to admit air to the same. In the axis of the fan-casing B' is mounted a shaft C, having the fan C attached. Said shaft is journaled 60 in the end walls of the case A and provided with a driving-pulley H on its outer end, engaging the drive-wheel D of the sweeper to rotate the fan and induce an inward current of air between the case and the carpet and an 65 outward current of air from said fan through the passage B.

In operation the sponge G is moistened with water, and the current of air inward beneath the case and outward through said sponge 70 prevents the light dust from escaping from beneath the case and carries it into the sponge, where it is retained and from which it is easily removed by washing the sponge in water.

Having thus fully described my invention, 75 what I claim, and wish to secure by Letters Patent, is—

1. The combination of a carpet-sweeper case having an opening for egress of air, a shaft having a pulley to engage a drive-wheel 80 of the sweeper a fan on said shaft, a casing and air-passage formed by a continuous strip of sheet metal extending horizontally from the lower side of said opening to near the middle of the case, and thence in a curve 85 about the axis of said shaft, and end plates having openings around said shaft, and a sponge in said passage, substantially as described.

2. In a carpet-sweeper, a case having an 90 egress-opening and a door in its top, an air-passage below said door, screens at each end of said air-passage, a sponge in said passage, a fan-casing at the inner end of said passage having axial openings, a shaft in the axis of 95 said casing having a pulley engaging the drive-wheel of the sweeper, and a fan on said shaft, substantially as described.

3. In a carpet-sweeper the combination of a case having an opening in one of its inclined 100 sides, and a door in its top adjacent to said opening, a shaft journaled in said case, a fan

and pulley on said shaft, a drive-wheel enga-
gaging said pulley and supporting the case,
a strip of sheet metal less than the width of
the case extending horizontally from the lower
5 side of the said opening to near the middle of
the case and thence in an incomplete cylinder
around the shaft, end plates having openings
around said shaft, a screen between the fan
and the door, a screen in the opening of the

case and a sponge in the air-passage and be-
tween said screens substantially as described.

In testimony whereof I affix my signature
in presence of two witnesses.

BRODERICK HASKELL.
